COMBINED VALVE CASING AND SPRINKLER

Mario Anesi, 1/2 Ansan Tool and Manufacturing Co. Inc.,
4750 N. Ronald St., Chicago, Ill. 60631

Filed Apr. 1, 1966, Ser. No. 1,726

Term of patent 14 years

(Cl. D91—1)

FIG. 1 is a front elevational view of the combined valve casing and sprinkler, showing my new design;

FIG. 2 is a rear elevational view thereof;

FIG. 3 is a top plan view thereof;

FIG. 4 is a vertical end view thereof, taken from the right side of FIG. 1;

FIG. 5 is a vertical end view thereof, taken from the left side of FIG. 1;

FIG. 6 is a bottom view thereof;

FIG. 7 is a vertical sectional view taken along the line 7—7 of FIG. 1, looking in the direction of the arrows; and

FIG. 8 is a horizontal sectional view thereof, taken along the line 8—8 of FIG. 1, looking in the direction of the arrows.

The portions shown in broken lines are included for illustrative purposes only.

I claim:

The ornamental design for a combined valve casing and sprinkler, as shown and described.
